SWITCH

Clarence F. Gibson, Benicia, Calif.

Application February 4, 1947, Serial No. 726,294

3 Claims. (Cl. 200—83)

1

This invention relates to new and useful improvements and structural refinements in switches, more specifically, electric switches, and the principal object of the invention is to provide a device of the character herein described, such as may be conveniently and effectively employed in association with internal combustion engines on automobiles, or the like, for the purpose of automatically discontinuing the supply of electric current to the ignition system when, for some reason, the oil pressure falls below normal.

A further object of the invention is to provide a switch which may be used in such manner as not to interfere with the normal delivery of electric current to the ignition system before the oil pressure is built up, while the engine is being started.

Another object of the invention is to provide a switch which is simple in construction, dependable in operation and which, in view of its function, will prevent considerable damage to the engine, such as frequently results when the latter is operated with low or without any oil pressure.

An additional object of the invention is to provide a switch which may be easily and conveniently adjusted, so as to open the ignition circuit as soon as the oiling system falls to a predetermined pressure. It will be apparent that in this manner, the invention will also eliminate undue loss of current from the storage battery, which frequently occurs when the operator of the engine forgets to turn off the conventional ignition switch.

A still further object of the invention is to provide a switch which may be readily installed in position, which may be easily disassembled for purposes of inspection or repair, and which will readily lend itself to economical manufacture.

With the above more important objects in view, and such other objects as may become apparent as this specification proceeds, the invention consists essentially of the arrangement and construction of parts as illustrated in the accompanying drawings, in which:

Figure 1 is a cross-sectional view of the invention, taken substantially in the plane of the line 1—1 of Figure 2.

Figure 2 is a top plan view of the device shown in Figure 1, and

Figure 3 is a wiring diagram, showing the invention in use.

Like characters of reference are used to designate like parts in the specification and throughout the several views.

Referring now to the accompanying drawings in detail, the invention consists of a switch designated generally by the reference numeral 10, the same embodying in its construction a substantially cylindrical housing 11, provided at the ends thereof with out-turned flanges 12 and 13.

2

It will be noted that the end of the housing adjacent the flange 13 is closed as indicated at 15, while a removable cover 16 is secured to the flange 12 at the relatively opposite end of the housing by means of suitable screws 17.

A dome-shaped cap 18 is removably attached to the flange 13 by a plurality of further screws 19, and a diaphragm 20 is interposed between the flange and the cap, as is best shown in Figure 1.

10 It will be also observed that the cap 18 is provided with a screw-threaded boss 21, the latter being adapted to receive an oil pressure line 22 which communicates with the oiling system of the engine with which the invention is used.

15 It will be seen from the foregoing that the interior of the cap 18 provides what may be referred to as a fluid chamber 23 which is further defined by the diaphragm 20.

20 Similarly, the interior of the housing 11 constitutes a mechanical chamber 24 which provides an enclosure for, inter alia, a cylindrical guide 25.

25 The guide 25 is formed integrally with the closed end 15 of the housing 11, and said closed end is formed with an aperture 26 which communicates with the interior of the guide, as will be clearly apparent. In effect, the aperture 26

25 constitutes a continuation of the bore of the guide 25, the remaining end of the guide being closed as indicated at 27 and being formed with a further aperture 28.

30 A plunger 29 is slidably positioned in the aperture 28 and is screw-threaded at one end thereof (as at 30) into a dome-shaped end piece 31 which, in turn, contacts the diaphragm 20. It will be noted that the end piece 31 is slidably disposed in the opening 26 and in the cylindrical guide 25, as will be clearly understood.

35 The inner end of the plunger 29 is provided with a disc 32, while the inner surface of the cover 16 is formed integrally with a tubular sleeve 33.

40 An adjusting screw 34 is threaded into this sleeve through a suitable opening provided in the cover 16, and a compression spring 35 is interposed between the screw 34 and the disc 32. The sleeve 33 constitutes what may be referred to as a seat or guide for the spring 35, and the primary purpose of the spring is to urge the plunger 29 and the associated end piece 31 toward the diaphragm 20. The screw 34 is provided with a suitable lock nut 36, for obvious reasons.

45 A bell crank 37 is pivoted as at 38 to a bracket 39 secured to the inner surface of the housing 11, one arm of the bell crank being disposed between the closed end 27 of the guide 25 and the disc 32 of the plunger 29. The remaining arm of the bell crank 37 carries a conductive member or portion 40 which, in turn, is provided with a contact point 41. A coating contact point 42 is mounted on an insulated conductor ring 43 secured to the

guide 25, the point 42 being stationary, as will be clearly apparent.

The lateral wall of the housing 11 is provided with a pair of terminal posts 44 and 45, these, of course, being insulated with respect to the housing and simply assuming the form of suitable screws, insulating washers and nuts, substantially as shown in Figure 1. The post 45 is electrically connected by means of a wire 46 to the conductor ring 43, while a leaf spring 47, configurated substantially as shown, is secured to the terminal post 44. The free end portion of the spring 47 bears against the adjacent arm of the crank 37 and the spring thus performs a double function, namely, that of electrically connecting the post 44 to the contact 41 through the medium of conductive member 48, and urging the other arm of the bell crank against the disc 32.

With particular reference to the accompanying Figure 3, the terminal post 44 is connected by means of a conductor 48 to one pole 49 of a storage battery 50, the remaining pole of the battery being grounded in the conventional manner, as indicated at 51. The battery pole 49 is also connected by means of a conductor 52 to one contact 53 of a "two way" ignition switch 54. The remaining contact 55 of the switch 54 is connected as at 56 to the terminal post 45 of the switch 10, and the terminal 57 of the switch 54 is connected at 58 to the distributor of the engine with which the invention is employed. The switch 54 is, of course, manipulated by means of a suitable handle 59.

When the invention is placed in use, the spring 35 (which is relatively stronger with respect to the spring 47) will normally urge the plunger 29 against the diaphragm 20, as has been already explained.

In such event, the points 41 and 42 will be separated and no current will be delivered through the open switch 10 from the battery 50 to the distributor of the engine. However, the engine may be started by simply manipulating the lever 59 so as to complete the circuit between the contact 53 and the terminal 57, and as soon as oil pressure exists in the chamber 23, the diaphragm 20 will force the plunger 29 against the resiliency of the spring 35, thereby permitting the contacts 41, 42 to become engaged in a circuit-closing position, under the influence of the spring 47. Current will now pass through the switch 10, and the arm 59 of the switch 54 may be set so as to establish electrical connection between the contact 55 and the terminal 57.

Thereupon, the ignition system of the engine will be dependent for its supply of electricity entirely upon the switch 10, and in the event that the oil pressure falls to normal, the resiliency of the spring 35 will overcome the resiliency of the spring 47 and the contact points 41, 42 will be automatically separated.

It will be apparent that in this manner, the engine will be stopped as soon as the oil pressure drops below normal, this action being governed by the resiliency of the spring 35. This, in turn, is governed by the setting of the screw 34 and the latter should, of course, be adjusted so that the points 41, 42 are separated as soon as the oiling system of the engine drops to a predetermined pressure.

It is believed that the advantages and use of the invention will be clearly understood from the foregoing and accordingly, further description thereof at this point is considered unnecessary.

While in the foregoing there has been shown

and described the preferred embodiment of this invention it is to be understood that minor changes in the details of construction, combination and arrangement of parts may be resorted to without departing from the spirit and scope of the invention as claimed.

What I claim as my invention is:

1. A pressure actuated switch comprising a housing having a bottom wall, a cylindrical guide integrally formed with the bottom wall, an opening provided in the bottom wall communicating with said guide, a plate integrally formed with said guide having a central opening, a piston rod slidably received in the opening in said plate, a piston carried by said rod slidably received in said guide and the opening in said bottom wall, a stop disk fixed to said rod and disposed exteriorly of said plate, a cap carried by said bottom wall, a diaphragm interposed between said cap and said bottom wall for moving the piston and piston rod, resilient means normally urging the piston against the diaphragm, a fixed contact point carried by the housing, a substantially L-shaped lever mounted in said housing for pivotal movement, a contact carried by the longer leg of said lever for engaging said fixed contact, and means acting on the longer leg of said lever for urging the contact thereon toward the fixed contact, the shorter leg of said lever being normally clamped between said plate and said stop to space said contacts.

2. A pressure actuated switch comprising a housing, a hollow support mounted in said housing including an upper wall, a fixed contact mounted in said housing, a substantially L-shaped lever mounted in said housing for pivotal movement, a contact carried by the longer leg of said lever, a sliding member mounted in the support and including an abutment for clamping the shorter leg of said lever against the upper wall to retain the contact carried by the lever spaced from the fixed contact, means urging the contact carried by said lever into circuit closing position with said fixed contact, and a diaphragm carried by the housing for moving the sliding member to urge the abutment from the shorter leg of said lever.

3. A pressure actuated switch comprising a housing, a support mounted in said housing including an upper wall, a fixed contact mounted in said housing, a substantially L-shaped lever mounted in said housing for pivotal movement, a contact carried by the longer leg of said lever, means for clamping the shorter leg of said lever against the upper wall and the contact carried by the lever spaced from the fixed contact, means urging the contact carried by said lever into circuit closing position with said fixed contact, and means for releasing said first mentioned means, said first mentioned means including a spring urged plunger having a stop adapted to bear against the shorter leg of said lever.

CLARENCE F. GIESON.
